CLAIM

We claim the ornamental design for a hand-held electronic device, as shown and described.

DESCRIPTION

FIG. 1 is a front perspective view of a hand-held electronic device;

FIG. 2 is a rear perspective view thereof;

FIG. 3 is a front elevational view thereof;

FIG. 4 is a right elevational view thereof;

FIG. 5 is a left elevational view thereof;

FIG. 6 is a bottom plan view thereof;

FIG. 7 is top plan view thereof; and,

FIG. 8 is a rear elevational view thereof.

The broken lines shown in FIGS. 1 and 3, that are immediately adjacent the shaded areas and encompass non-shaded regions represent the bounds of the claimed design, while all other broken lines are directed to environment and are for illustrative purposes only; the broken lines form no part of the claimed design.
